FIRING SWITCH FOR ROCKET LAUNCHERS

Paul T. Nims, Detroit, Mich., assignor to Chrysler Corporation, Highland Park, Mich., a corporation of Delaware

Application August 19, 1947, Serial No. 769,351

3 Claims. (Cl. 171—209)

1

This invention relates to a new and useful improvement in firing switches for rocket launchers and is designed to provide a device for firing electrically ignited rockets by manual operation of a magneto and coil. The particularly novel and useful feature of the device is the peculiar relation of a current generation means and a distributor so that peak current generation and the circuit closing precisely coincide. Another valuable feature is the actuation of the magneto by the manual driving means through an impulse coupling, the magneto responding to the impulse of spring means precisely tensioned by the manual driving means. The novel structure effects uniform high-speed actuation of the magneto to produce the current of voltage requisite for firing, regardless of the speed of the manual driving means. The mechanism is capable of reverse movement whereby the distributor can be "set" for initial firing of a selected rocket, or a plurality of selected rockets. This movement is effected by mere reversal of direction of movement of the manual driving means, the device requiring no adjusting modification and such reverse movement also permits adjustment of the distributor for effecting contact to such rockets as may have failed to ignite. The invention provides an improved electric switch suitable for many uses other than firing rockets, such as for instance for progressive or selective blasting. Certain specific embodiments of the invention are illustrated in the drawings filed herewith and are hereinafter fully described, but it is to be distinctly understood that the invention is not considered to be limited to said specific embodiments, and that its scope is defined by the claims appended hereto.

In the drawings:

Figure 1 is a longitudinal, vertical section on the line 1—1 of Figure 2, in the direction of the arrows.

Figure 2 is a transverse, vertical section on the line 2—2 of Figure 1, in the direction of the arrows.

Figure 3 is a transverse, vertical section on the line 3—3 of Figure 1, in the direction of the arrows.

Figure 4 is an end elevation of the right end of the device as viewed in Figure 1.

Figure 5 is a horizontally transverse section on the line 5—5 of Figure 3, in the direction of the arrows.

Figure 6 is a top plan of the impulse coupling shown in vertical section in Figure 1.

2

Figure 7 is a transverse, vertical section on the line 7—7 of Figure 1, in the direction of the arrows.

Figure 8 is a transverse, vertical section on the line 8—8 of Figure 1, in the direction of the arrows.

Figure 9 is a view similar to Figure 8, the parts being shown in released position for driving.

Figure 10 is a view similar to Figures 8 and 9, the parts being shown in position for reverse movement.

Figure 11 is a vertical section through the rear portion of a rocket launcher frame, showing the electric contacts of the cable from the firing switch.

Figure 12 is a greatly enlarged section on the line 12—12 of Figure 11, in the direction of the arrows.

Figure 13 is a wiring diagram.

Figure 14 is a fragmentary, longitudinal, vertical section, similar to Figure 1, showing a modified form of distributor.

Figure 15 is a transverse, vertical section on the line 15—15 of Figure 14, in the direction of the arrows.

Figure 16 is an enlarged, fragmentary elevation of the indicator of the distributor of Figures 14 and 15, showing the parts in a different relation.

Figure 17 is a view similar to Figure 16, the parts being in other different positions.

Figure 18 is a wiring diagram of the modified form of the device.

As illustrated in the drawings (Figs. 1 to 13), the improved firing switch is mounted in a casing, of suitable non-magnetic material, having a rectangular bottom 1, side walls 2 and 3, and cover 4 provided with a carrying handle 5. The casing is provided toward the right end, as viewed in Figure 1, with a tubular portion 6 depending from cover 4 and spaced from bottom 1 to provide a recess 7 open at the end of the casing and closed by a vertical partition 8 from bottom 1 to top 4. The outer end of portion 6 is closed by a plate 9 attached to portion 6 by bolts 10 and having a central bore 11 and concentric socket 12. The portion of the casing to the left of partition 8 (Fig. 1) is rectangular, between bottom 1 and cover 4 and side walls 2 and 3, and is closed by a circular plate 13 attached to walls 2 and 3 by bolts 14 (Figure 2). A tubular housing 15, concentric with and of the same diameter as plate 13, is mounted thereon by bolts 16 (Figs. 1, 2 and 4). The operative elements of the improved firing

switch are mounted in the above-described casing.

A driving shaft 17 is journaled in bore 11 of plate 9 and provided with a sealing ring 18 in socket 12 held therein by cap ring 19 attached to plate 9 by bolts 20. Shaft 17 is socketed on its outer end protruding from cap ring 19 to receive therein the shaft 21 of crank handle 22 for rotating shaft 17.

The crank handle 22 can be stowed, when not in use in the recess 7, held therein by a clip 7—a on the outer face of the partition 8.

The shaft 17 is provided on its inner end with a head 23 having a pair of female coupling members 24 to receive therein the male coupling members 25 on a drum 26 co-axial with shaft 17. A helical spring 27 disposed in drum 26 has its outer end 28 attached to drum 26 and its inner end 29 attached to a plate 30, by a post 31 mounted on plate 30 and projecting into drum 26. Plate 30 is keyed on a driven shaft 32 journaled in aligned bearings 33 and 34 in partition 8 and plate 13, respectively, co-axial with shaft 17. It will be noted (Fig. 1) that the right end of shaft 32 is slightly spaced from the left end of head 23 of shaft 17, and has threaded therein a cap nut 35 with a sleeve 36 about shaft 32 serving as a bearing for central flange 37 of drum 26 thereby mounted for free rotation about shaft 32 between cap nut 35 and plate 30. Plate 30 has a circular flange 38 concentric with shaft 32 and projecting into drum 26 adjacent flange 37 of drum 26. Plate 30 has a central sleeve 39 about shaft 32 spacing plate 30 from bearing 33 in partition 8. Plate 30 has, at diametrically opposite portions on its periphery, radial extensions 40 and 41 forming abutments 42. Plate 30 has a pair of pintles 43, diametrically spaced from sleeve 39, on which are pivoted latches 44 and 45 having heads 46 having straight edges 47 and convex ends 48 concentric with pintles 43, and tails 49 having inner concave edges 50 and outer shoulders 51. Drum 26 has a pair of lugs 52 and 53 on diametrically opposite sides of drum 26 and projecting parallel with axis of shaft 32 over plate 30 for co-action with edges 47 of heads 46 of latches 44 and 45, and with abutments 42 of extensions 40 and 41 (Figs. 8, 9, 10).

A cylindrical stop-pin 54 is mounted on partition 8 adjacent sleeve 39 and so disposed as to engage the convex ends 48 of heads 46 of latches 44 and 45 when heads 45 swing outwardly (Fig. 8) when latches 44 and 45 pivot about pintles 43.

The shaft 32 has, on its end projecting from bearing 34 in plate 13, a pinion 55 which meshes with a gear 56 fixed on a shaft 57 journaled in bearing 58 in plate 13. A pinion 59 fixed on shaft 57 meshes with a gear 60 on a hollow shaft 61 journaled in a bearing 62 in plate 13.

The shaft 32 carries the magneto rotor composed of two permanent magnet blocks 63 welded between shoes of soft magnetic material 64 clamped by bolts 65 between non-magnetic plates 66 suitably mounted on shaft 32. The shoes 64 and plates 66 have convex ends 67 concentric with shaft 32 and the blocks 63 have convex ends 67—a concentric with shaft 32 and on radii inferior to the radii of ends 67 (Fig. 3). The magneto pole shoes 68 are hung from a non-magnetic bridge 69 arched above the rotor and suspended from cover 4. The shoes 68 are composed of soft magnetic material having concave portions 70 concentric with shaft 32 and of slightly greater radius than that of convex ends 67 of the rotor, and recessed portions 71 on their lower ends (Fig.

3). Adjacent the recessed portions 71 of the pole shoes 68 of the magneto, there is a support bracket comprising a depending plate 72 suitably bolted to the partition 8 of the casing, and a pair of arms 73 between which is disposed a coil 74, its core 75 being engaged between the ends of pole shoes 68 and arms 73 by pins 76 threaded through arms 73, thereby connecting shoes 68 by core 75.

The ends of the coil winding have leads 77 and 78 (Fig. 5) to the distributor and a ground wire, as shall be presently explained. Lead 77 (Fig. 1) is connected by terminal 79 and binding post 80 to a spring contact plate 81 mounted by binding posts 80 and 82 on an insulated block 83 mounted on plate 13 adjacent its bearing 62. The upper free end of plate 81 bears in electrical contact on a metallic boss 84 on the end of, and integral with a sleeve 85 mounted in the end of a bored shaft 86 seated in the hollow shaft 61 and having on its other end an integral disc 87. Shaft 86 and disc 87 are of insulating material. A second disc 88 of insulating material is disposed on the outer side of disc 87 and both discs 87 and 88 are pinned to gear 60 by rivets 89. Shafts 61 and 86, gear 60 and discs 87 and 88 are concentric. Disc 88 has a radial arm 90 on which is mounted an electric contact member 91 connected to sleeve 85 by a conductor 92 which passes through the centers of discs 87 and 88 and the bore of shaft 86, and has its end seated in sleeve 85.

The distributor casing comprises a hexagonal base flange 93 mounted on plate 13 by bolts 94 (Figs. 1 and 2), a cylindrical wall 95 and a circular cover 96. The flange 93, wall 95 and cover 96 are integral and composed of suitable transparent insulating material, such as Lucite. Suitably mounted in the wall 95 there are twenty-eight contact plates 97 disposed radially of and symmetrically about the said concentric shafts 61 and 86 and discs 87 and 88. The contact member 91 has an arcuate flexible portion 98 extending radially beyond the outer end of radial arm 90 and so disposed as to effect a wiping contact with each contact plate 97 when arm 90 and contact member 91 are rotated. It will be noted (Fig. 2) that the spacing of plates 97 and curvature of portion 98 are such that the wiper portion 98 passes off of the plates 97, to break the circuit, in its passage from one plate 97 to the next. Each plate 97 has a binding post 99, passed through wall 95, to which is connected an insulated wire 100. The wires 100 are led from the distributor casing, in the tubular housing 15, to

an outlet 101 radial of housing 15, and connected to suitable contacts in a suitable terminal block 102 of a coupling 103 for connecting thereto a suitable terminal block 104 of a cable 105 to the rocket launcher frame. It is to be noted (Fig. 13) that lead 78 from the coil 74 is connected by a wire 106 to a contact in the block 102 for connection to the ground wire 107 of cable 105.

The other end of cable 105 has a similar terminal block for coupling to a similar terminal block of an inlet 108 of frame 109 which has wires 110 connecting the contacts of the terminal block with contact points 111 of the sockets 112 for the rockets, respectively. A wire 113 connects the contact in the terminal block with which ground wire 107 of cable 105 is connected, with a contact lug 114 grounded on frame 109. It will be noted (Fig. 12) that wires 110 and contact points 111 are insulated from frame 109 by insulation blocks 115 and collars 116 about binding posts 117.

The modified form of the device, shown in Figures 14 to 18, has the crank handle, driving shaft and its coupling, the impulse coupling, driven shaft, magneto and coil, as in the form shown in Figures 1 to 13. It has a plate 118, attached to the casing by bolts 119, in which is journaled the driven shaft 120, in bearing 121, with pinion 122 meshing with gear 123 on shaft 124 journaled in bearing 125 in plate 118 and having pinion 126 meshing with gear 127 on hollow shaft 128 journaled in bearing 129 in plate 118. The lead 130 from the coil 74 has its terminal 131 connected to insulatedly mounted spring contact plate 132 pressed against boss 133 of sleeve 134 in bored insulation shaft 135 in hollow shaft 128 and having the integral disc head 136 mounted on insulating washer 137 on gear 127 which is attached to washer 137 and head 136. A spring-pressed contact arm 138 is attached to and extends radially from head 136 and is connected with sleeve 134 by a conductor 139 which passes through head 136 and shaft 135.

The modified form of distributor has a housing 140 comprising a bottom 140-a, a top 140-b, sides 140-c and 140-d, and end wall 140-e and an outwardly turned, peripheral, base flange 140-f, attached to plate 118 by bolts 141. A distributor plate 142 comprising a circular disc of insulating material is mounted on end wall 140-e by bolts 143. Suitably mounted in plate 142 there are twenty-eight contact plates 144 disposed symmetrically in a circle concentric with shafts 128 and 135. The parts are so related that the outer end of contact arm 138 effects a wiping contact with each plate 144 when arm 138 is traversed over face of disc 142 by rotation of shaft 135. It will be noted (Figures 14 and 15), that arm 138 has a projection 138-a to effect said contact and that the width of projection 138-a and the relative spacing of plates 144 are such that contact arm 138 passes off of the plates 144, to break the circuit, in its passage from one plate 144 to the next (Figure 15). Each plate 144 has a shank 145 provided with four terminals 146 in which are connected wires 147-a, 147-b, 147-c and 147-d, respectively (Figures 15 and 18, which are led through housing 140 to four outlets 148-a, 148-b, 148-c and 148-d in the sides 140-c and 140-d of housing 140, respectively (Figure 15). Said wires are connected by terminal blocks and couplings, as in the form of the device above described, with wires in cables 149 connecting the firing switch to four rocket launcher frames 150, respectively. It will be noted (Figure 18) that lead 151 of the coil 74 is connected by wire 152 to wires 153-a, 153-b, 153-c and 153-d which are connected, through cables 149, respectively, with the wires grounded on frames 150, respectively.

Since the distributor housing 140 is made of opaque material and the rotatable contact arm 138 cannot, therefore, be observed by the operator, the device is provided with a semaphore for indicating the position of the contact arm 138 when firing is to be commenced. A suitable insulated block 154 is suspended from the top 140-b of the distributor housing 140, on which is pivoted a semaphore arm 155 having an angularly displaced finger 156 extending into the path of travel of the contact arm 138. A sight opening 157 in top 140-d may be closed by a plug of transparent material such as Lucite. The parts are so related that, when the contact arm 138 is disposed so as to position its projection 138-a intermediate the contact plate 144 at the zenith

of the vertical diameter of distributor plate 142 and marked with the numeral "1" (Fig. 15) to indicate that it is the contact for firing No. 1 rocket in each frame 150, and the next contact plate 144 to the left (Fig. 15) which is the contact for firing No. 28 rocket in each frame 150, the semaphore arm 155 is brought co-axial with sight opening 157 and can be observed. Stop pins 158 in block 154 serve to limit the movement of arm 155.

The device, illustrated in Figures 1 to 13, operates as follows. When the crank handle 22 has been connected with the driving shaft 17 and its outer portion is horizontally disposed (Figures 1 and 4), the rotor of the magneto is so disposed that its convex ends 67 are positioned between the pole shoes 68 and its convex ends 67-a adjacent shoes 68, respectively (Figure 3), and the wiper portion 98 of the contact member 91 of the distributor is positioned intermediate two of the contact plates 97 (Figure 2). The impulse coupling is positioned as shown in Figures 1, 6, 7 and 8. It will be noted (Figure 8) that plate 30 is so disposed that the pintle 43, on which is pivoted latch 44, is above the horizontal diameter of plate 30 casing tail 49 of latch 44 to drop, its inner edge 50 contacting sleeve 39 of plate 30, thereby projecting head 46 of latch 44 radially of plate 30, the convex end 48 of head 46 engaging stop-pin 54 thereby immobilizing plate 30 and shaft 32 against rotation.

The crank handle 22 is moved clockwise (Figure 4) from horizontal position to the right to horizontal position to the left. This half revolution of crank 22, through shaft 17, head 23 and coupling members 24 and 25 rotates drum 26 through an arc of 180°.

This rotation of drum 26, about immobilized shaft 32, puts spring 27 under tension and moves drum lug 52, through an arc of 180°, from its position shown in Figure 8 to the position of lug 53 in Figure 8. When lug 52 has moved through an arc of 90° to the position shown in Figure 9, it has moved over edge 47 of head 46 of latch 44 to retract latch 44, the convex end 48 of head 46 moving off of the arcuate surface of stop-pin 54. This retraction of latch 44 releases plate 30 which is rapidly rotated, with shaft 32, under the impulse of tensioned spring 27. It will be noted (Figures 8 and 9) that this spring-actuated rotation of plate 30 brings pintle 43 of latch 44 above the horizontal diameter of plate 30 causing tail 49 of latch 44 to drop thereby projecting head 46 of latch 44, so that when by the said rotation of plate 30 the latch 44 is brought to the position in which latch 44 is shown in Figure 8, the end 48 of head 46 of latch 44 will engage the stop-pin 54, thereby again immobilizing the plate 30 and shaft 32 after their rotation through an arc of 180°.

This rapid movement of shaft 32, driving the rotor of the magneto through an arc 180°, counter-clockwise, as viewed in Figure 3, causes the magneto to perform its normal function, viz. this movement of the rotor produces a flux change in the magnetic circuit which links the coil 74, producing an electric current of the desired voltage. It will be understood that due to the driving of the rotor by the tensioned spring 27, the rotor moving through an arc of 90° at increasing speed produces peak current generation in coil 74, and moving through the remaining 90° of its travel at decreasing speed produces diminishing current in coil 74.

The rotation of shaft 32 drives shafts 61 and

86, through their associated gearing, thereby moving wiper contact 98 onto its adjacent contact plate 97, and closing the circuit from coil 74 to the suitable electric firing mechanism in one of the rockets in the frame 109.

It is to be understood that the parts are so designed and related that the circuit closing and current generation precisely coincide, so that the wiper contact 98 passes the axis of each contact plate 97, closing the circuit, during the peak current and moves from one contact plate 97 to the next during an interval of small or zero current.

It will be noted that, by reason of the driving of the magneto rotor by the tensioned spring 21 of the impulse coupling, uniform high speed rotation is effected, regardless of the speed of rotation of hand crank 22, to produce the desired rapid flux change generating the proper current to fire the rockets.

As the distributor casing is transparent, the wiper contact 98 and contact plates 97 are observable, permitting adjustment of contact 98 relative to the plates 97, preliminary to operation of the device for firing. To set the contact 98, as for instance to condition the device for firing No. 1 rocket by effecting contact between plate 98 and the plate 97 at the zenith of the vertical diameter of the distributor casing, the crank handle 22 is rotated counter-clockwise, as viewed in Figure 4. Such rotation causes shaft 17, head 23 and coupling members 24 and 25 to drive drum 26 counter-clockwise. Lugs 52 and 53, engaging abutments 42 of extensions 40 on plate 30, effect direct drive of plate 30 and shaft 32 (Figure 10). Straight edges 41 of heads 46 of latches 44 and 45, striking stop-pin 54, retract latches 44 and 45. Such rotation of shaft 32 effects such low-speed movement of the magneto rotor relative to pole shoes 68 that the coil 74 does not produce any current. Therefore, contact 98 passes, in this direction (clockwise as viewed in Figure 2), over plates 97 innocuously. It is obvious that the device can be thus conditioned to effect contact with any selected plate 97 on the initial operative rotation of crank handle 22, for initially firing a selected rocket in the frame 109.

In the device illustrated in Figures 14 to 18, the means for driving shaft 120 function as above described and rotation of shaft 120 causes the magneto and coil to supply the current to the distributor, and operate the distributor as above described. It is obvious that when contact arm 138 is brought into contact with one of the plates 144, a circuit is closed from the coil to the firing mechanism of one rocket in each of the four frames 150, to discharge a salvo of four rockets.

As above described, the signal semaphore 155 is provided to indicate that contact arm 138 is positioned to effect contact with plate 144 for firing No. 1 rocket in each frame 150, on initial operative rotation of crank handle 22. It is obvious that contact arm 138 can be so positioned, in the same way that contact 98 is positioned, as above described. When arm 138 moves away from finger 156 (clockwise as viewed in Figure 15), on firing, the finger 156 moves by gravity to swing arm 155 away from sight opening 151 (Figure 16). When finger 156 is in the path of arm 138, moving in either direction, it will be deflected, as shown in Figure 17, uninterfering with movement of arm 138.

It will be noted that the magneto disclosed herein comprises a coil 74 in which all of the flux changes linking the coil are produced directly in the coil by rotation of the magnet rotor.

Furthermore, the magneto operates with a simple generator action to produce current which is passed directly from this coil to the rotatable contact member 91 without requiring primary and secondary coils or breaker points of conventional magnetos. The magneto thus eliminates the most troublesome and perishable items of conventional magnetos thereby providing a device having the desired characteristics of ruggedness, durability, and long dependable life under conditions encountered in the field incident to launching rockets as well as for progressive or selective blasting operations for road building, quarry, or mining work.

Having described the invention, what I claim is:

1. In an electric switch, the combination of a casing having a pair of removable, parallel end walls, an integral intermediate partition parallel therewith, and a top; a driving shaft, having a removable crank handle, journaled in one end wall; a driven shaft, co-axial with said driving shaft, journaled in the other end wall and said partition; an impulse coupling connecting said shafts; a magneto rotor mounted on said driven shaft; a pair of magneto pole shoes, suspended from said top, relatively spaced on the sides of said rotor, respectively; a coil having a core supported from said partition and connecting said shoes, said coil having two leads from its ends, respectively; a second driven shaft journaled in the end wall in which said first driven shaft is journaled; gearing connecting said driven shafts; a distributor housing mounted on the end wall in which said driven shafts are journaled; a plurality of electrical contacts mounted in said housing and arranged symmetrically in a circle concentric with said second driven shaft; a contact arm mounted on said second driven shaft for effecting electrical contact between said arm and said distributor contacts successively when said second driven shaft is rotated; an electrical connector between one of said coil leads and said contact arm; and means, mounted on said casing, for connecting said switch with a plurality of electrically operated mechanisms, said connecting means having an electrical connector to the other coil lead, and a plurality of electrical connectors to said distributor contacts, respectively.

2. In an electric switch, the combination of a casing having a pair of removable, parallel end walls, an integral intermediate partition parallel therewith, and a top; a driving shaft, having a removable crank handle, journaled in one end wall, a driven shaft, co-axial with said driving shaft, journaled in the other end wall and said partition; an impulse coupling connecting said shafts; a magneto rotor mounted on said driven shaft; a pair of magneto pole shoes, suspended from said top, relatively spaced on the sides of said rotor, respectively; a coil having a core supported from said partition, and connecting said shoes, said coil having two leads from its ends, respectively; a second driven shaft journaled in the end wall in which said first driven shaft is journaled; gearing connecting said driven shafts; a distributor housing mounted on the end wall in which said driven shafts are journaled; a plate of insulating material mounted in said housing normal to said second driven shaft; a plurality of electrical contacts mounted in said plate and arranged symmetrically in a circle concentric with said second driven shaft; a contact arm mounted on said second driven shaft for effecting electrical contact between said arm and said distributor contacts successively when said second driven shaft

is rotated; an electric connector between one of said coil leads and said contact arm; and a plurality of means, mounted on said housing, for connecting said switch with a plurality of sets of electrically operated mechanisms, respectively, each of said connecting means having an electrical connector to the other coil lead, and a plurality of electrical connectors to said distributor contacts, respectively.

3. In an electric switch, the combination of a 10 casing having a pair of parallel end walls, an integral intermediate partition parallel therewith, and a top; a driving shaft having a removable crank handle, journaled in one end wall; a driven shaft co-axial with said driving shaft, journaled 15 in the other end wall and said partition; an impulse coupling connecting said shafts; a magneto rotor mounted on said driven shaft; a pair of magneto pole shoes supported by said top, relatively spaced on the sides of said rotor, respectively; a coil having a core connecting said shoes, said coil having two leads from its ends, respectively; a second driven shaft journaled in the end wall in which said first driven shaft is journaled; gearing connecting said driven shafts; 20 a distributor housing mounted on the end wall

5 in which said driven shafts are journaled; a plurality of electrical contacts mounted in said housing and arranged concentric with said second driven shaft; a contact arm mounted on said second driven shaft for effecting electrical contact between said arm and said distributor contacts successively when said driven shaft is rotated; an electrical connector between one of said coil leads and said contact arm; and means mounted on said casing, for connecting said switch with a plurality of electrically operated mechanisms.
